POWER HAMMER RAM GUIDE

John W. O'Donnell, Chicago, Ill.

Application July 26, 1946, Serial No. 686,582

2 Claims. (Cl. 308—3)

1

This invention relates to a power hammer ram guide and more particularly to a ram guide construction for a steam forging hammer.

Conventional power hammers include a ram, usually having a die attached to the lower surface thereof, which is movable vertically between guide columns. To guide the ram, solid guide members are positioned along the inner sides of the guide columns, and these guide members have ribs thereon which mate with corresponding ribs on the ram thereby maintaining the ram against transverse movement. In these constructions, and taking a steam actuated forging hammer as an example, the solid guides are not readily removable because the ram blocks their removal and hence it is not possible to remove the ram from between the guide columns without extensive work which usually involves dismantling the cylinder into which the steam actuated piston extends. This piston, of course, is connected to the ram and moves it.

Despite the fact that it is laborious to remove the ram from between the guide columns, it is frequently necessary to remove the ram in order to dress the die seat and to make other adjustments and repairs. In order to overcome the disadvantage of conventional constructions, wherein solid guide members are provided and the ram can only be removed from between the guide columns after extensive dismantling, I provide a ram guide construction which is readily detachable from the guide columns even when the ram is in position between these columns thereby greatly facilitating the task of removing the ram from between these columns. My invention contemplates forming each ram guide into parts or sections with one section locking another other section in position against the guide column. When the ram is moved to one position, say lowered, the first, or locking, section is uncovered, that is, is free from engagement with the ram, and hence the first section can be unbolted and removed from the guide column. When this is accomplished, the ram can be moved to another position, say raised, to uncover or free the other section from engagement with the ram, following which the other section can be unbolted and removed from the guide column. In this manner the ram can be freed from engagement with the guides to permit it to be removed from between the guide columns. This is in contrast to conventional constructions wherein solid ram guides are provided and it is not possible, in normal movement of the ram, to move the ram out of engagement with the ram guide to permit the

2

guide to be removed from the guide column. In other words, the solid ram guides are so long that they are always engaged by the ram even when it is in its extreme upper position or lowered position of normal movement and hence they are always blocked from movement away from the guide columns by the ram. It is only by moving the ram to an abnormal position, as by dismantling the steam cylinder, that the solid guides can be removed. Naturally, this is a time consuming operation and, with my construction, the ram can be removed in a fraction of the time that it now takes.

Accordingly, it is an object of the present invention to provide a new and improved power hammer ram guide which is quickly and easily removed from the guide columns to permit the ram to be removed from between these columns.

It is another object of the present invention to provide a new and improved power hammer ram guide which is seated in a guide column and which is formed in parts or sections, each of which is readily removable from the guide columns to permit the ram to be moved from between the guide columns.

It is another object of the present invention to provide a new and improved power hammer ram guide which is adapted to be seated in a guide column and which is formed in parts, or sections, which are positioned in alignment and in which adjacent sections contact each other throughout a non-planar area of contact.

It is a further object of the present invention to provide a new and improved power hammer ram guide which is formed in parts or sections, said parts or sections being readily removable from a guide column, and in which the parts or sections are positioned in alignment with adjacent sections contacting each other through a non-planar area of contact, one of said sections locking the other against movement outward from the guide column.

It is a still further object of the present invention to provide a new and improved power hammer ram guide which is formed in sections, said sections being positioned in alignment, with adjacent sections contacting each other throughout a non-planar area of contact, and wherein each section has a plurality of guide ribs formed thereon, the guide ribs in one section being positioned in alignment with the guide ribs in an adjacent section.

These and other objects and advantages of my invention will become apparent from the follow-

ing detailed description taken in conjunction with the attached drawings in which:

Figure 1 is a front elevational view of part of a steam hammer, with part of one guide column therefor being shown in cross section to expose one of the ram guides and the retaining bolts therefor;

Figure 2 is a cross-sectional view taken on line II-II of Figure 1, and shows the ram, the ram guides and portions of the guide columns; and

Figure 3 is an isometric exploded view of a ram guide formed according to the teaching of my invention.

The embodiment of my invention shown in the drawings is illustrated as being used in connection with a steam forging hammer. As is conventional in such a type of hammer, a base 10 is provided which supports a work die 11 and upon which is mounted a pair of upstanding guide columns 12 and 13. A ram 14 is movable vertically between guide columns 12 and 13 and a die 15 is secured to the lower surface of the ram. The ram 14 is moved in response to movement of a steam-actuated piston 16. To guide the ram 14 for up and down movement between the guide columns 12 and 13, a pair of ram guides 17 and 18 are provided.

Each of the guide members 17 and 18 is seated in a guide column as can be observed in Figure 2. Thus, the guide member 17 is seated in guide column 12 and the guide member 18 is seated in the guide column 13. Each guide member is detachably secured to its respective guide column. To illustrate this, the guide member 17 is detachably secured within the recess or seat 19 of guide column 12 by means such as bolts 20 and 21. The tapered spacing blocks 22 and 23 are provided for the purpose of adjusting the distance between the ram guides 17 and 18 in order to maintain these guides in proper guiding engagement with the ram 14.

As both of the ram guides 17 and 18 are identical only one, guide 17, will be described in detail. This ram guide is shown in isometric view in Figure 3, where it will be noted that the guide includes two guide sections 24 and 25. When these sections are seated in guide column 12, guide section 24 is the upper section and is considerably shorter than guide section 25 which is the lower section. Guide section 25 has a shoulder surface 26 formed on its upper surface and guide section 24 has a shoulder surface 27 formed on its lower surface. When the two guide sections are seated in guide column 12, with guide section 24 being above guide section 25, the shoulder surfaces 26 and 27 are in contact with each other. The result is that the two guide sections 24 and 25 are positioned in alignment, being in continuation of each other, and the shoulder surface 27 locks the lower guide section 25 against movement away from the guide column 12. I refer to the area of contact between the guide sections 24 and 25, i. e., the area of contact which includes the shoulder surfaces 26 and 27 and the lower horizontal surfaces 34 and 35 on guide section 24 which contact the upper horizontal surfaces, not shown exposed, on guide section 25, as a non-planar area of contact. This is so because the shoulder surfaces cause part of the area of contact to be offset with respect to another part i. e. surface 35 is offset with respect to surface 34. The shoulder surfaces 26 and 27 are of even height so that there is a continuous area of contact between the guide sections 24 and 25.

A plurality of guide ribs 28 are formed on the

guide section 25 and these guide ribs are in alignment with a plurality of guide ribs 29 which are formed on guide section 24. The guide ribs 28 and 29 are in guiding engagement with cooperating ribs 31 formed on the ram 14. A similar construction is provided at the other side of the ram, i. e., the side that is guided by guide member 18.

Each guide section is provided with a bolt opening, the rim of which is adapted to be engaged by a bolt head. Thus when the bolt shank is passed through the bolt opening and the bolt head engages the guide section, the bolt is tightened at its opposite end and the bolt head will draw the guide section tightly against its associated spacing block to hold the guide section firmly within the guide column. As an illustration, the guide section 24 has a bolt opening 30 therein and the annular rim 31 of this bolt opening 30 is engageable by a bolt head, such as the bolt head on bolt 20, to hold guide section 24 securely against spacing block 22 within the recess or seat portion 19 of guide column 12. It will be noted that the bolt opening 30 is closely adjacent to the shoulder surface 27 which is formed on guide section 24. With this positioning of the bolt opening, when bolt 20 is drawn tight, pressure is applied to guide section 24 closely adjacent to the junction between this section and guide section 25 so that the shoulder surface 27 firmly and securely holds guide section 25 against movement. Similarly, the bolt member 21 securely holds the lower end of guide section 25 against movement, by virtue of the engagement of the bolt head with the annular rim portion 36, so that the effect is to have a two-part guide member as rigid and effective as if it were a one-piece or solid guide member.

Ram guide 18 is likewise formed in two parts or sections, like sections 24 and 25, and the sections of guide 18 are similarly retained within the recess or seat which is formed in guide column 13 by bolts like the bolts 20 and 21.

When it is desired to remove either ram guide from its seat in a guide column, the upper section of the ram guide is first removed. For example, the ram 14 would first be moved downwardly enough to uncover the upper section, such as section 24. Then the bolt 20 would be loosened and withdrawn, thereby permitting the guide section 24 to be withdrawn from the seat 19 in guide column 12. After guide section 24 has been withdrawn the ram 14 is moved upward enough to uncover section 25 following which bolt 21 is loosened and withdrawn thereby permitting guide section 25 to be withdrawn from seat 19. The travel of the ram 14 up or down to uncover either of the guide sections is within the normal limits of its travel so that it is not necessary to dismantle the actuating mechanism, such as a steam cylinder and piston arrangement, in order to move the ram out of engagement with the guides.

Ordinarily, the lower guide section, such as section 25, rests against a shoulder surface, such as 33, which restrains the guide section against vertical downward movement with respect to the guide column, such as guide column 12. Also when the upper guide section, such as 24, is bolted in position it restrains the lower guide section, such as 25, against vertical movement upward with respect to the guide column, such as 12.

In the manner just described, guide members 17 and 18 can both be readily removed from their respective guide columns and, when the guide members are removed, the ram 14 can be re-

moved from between the guide columns for the purpose of replacing the die 15 or for other necessary adjustments or repairs. It will thus be seen that I provide a multiple section ram guide which is easily removed from its associated guide column to permit the guided ram to be readily removed from between guide columns.

In conventional steam hammer constructions, where solid guide members are used to guide the ram in its up and down movement, the limits of normal travel of the ram do not enable it to clear or uncover the ram guides. Accordingly, it is necessary to move the ram to an abnormal position, as by dismantling the steam cylinder and piston arrangement, in order to clear the guides and permit them to be removed from the guide columns. This entails additional man-hours and expense. In my construction, each section of the ram guide can be uncovered, and hence removed, within the normal limits of travel of the ram, thereby eliminating the extra man-hours and expense caused by an extensive dismantling operation. Thus, each ram guide can readily be removed, following which the ram itself can be removed. With my construction I can accomplish removal of the ram from between the guide columns in approximately 4½ man-hours, as compared to approximately 40 man-hours for conventional structures utilizing solid ram guide members. Furthermore, although my ram guide is made in sections, these sections are firmly locked in place, with a shoulder joint therebetween which makes the whole guide structure rigid and the substantial equivalent, from a strength standpoint, of a solid guide structure.

While I have shown and described a particular embodiment of my invention I wish it to be understood that I do not intend to be restricted thereto, but that I intend to cover all modifications thereof which would be apparent to one skilled in the art and which come within the spirit and scope of my invention.

I claim as my invention:

1. In a power hammer or the like, an elongated vertically extending guide for a reciprocal ram comprising a pair of separable vertically aligned guide members, one of said members having a plurality of guide ribs formed in one vertical face thereof and a plane end face having a transverse

internal shoulder extending thereacross, and the other of said members having a corresponding plane end face abutting the end face of the one member and having a transverse external shoulder extending therebeyond and thereacross into abutment with the internal shoulder of said one member, said other member also having a plurality of guide ribs formed in one vertical face thereof for registry with the ribs of said one member upon assembly, the cooperating shoulders of said members accommodating separation of said members upon merely vertical relative movement thereof.

2. In a power hammer, a ram having vertical guide grooves formed on opposing side faces thereof, a supporting post on each side of said ram, and a vertically extending ram guide on each of said posts for guiding reciprocal vertical movement of said ram, said guides each comprising complementary vertically aligned guide members separably secured to one of said posts, one of said members having a plurality of guide ribs formed in one vertical face thereof and a recessed transversely extending plane shoulder formed in one end face thereof, and the other of said members having a projecting transversely extending plane shoulder formed in one end face thereof for mating engagement with the recessed shoulder of said one member upon assembly, said other member also having a plurality of guide ribs formed in one vertical face thereof for registry with the ribs of said one member upon assembly, said separable members being individually removable from said posts upon movement of said ram therebetween without disassembly of the ram from the hammer.
